ABSTRACT OF THE DISCLOSURE

A process for hardening gelatin which comprises reacting the gelatin with at least one compound represented by the formulae:

wherein R₁ represents a member selected from the group consisting of a hydrogen atom, an alkyl group, a halogen-substituted alkyl group, an alkoxyalkyl group, an aryl group and an aryloxyalkyl group; R₂ represents a member selected from the group consisting of an alkyl group, a halogen-substituted alkyl group, an alkoxyalkyl group, an aryl group and an aryloxyalkyl group; and Z represents non-metallic atoms requisite for forming a carbon ring selected from the group consisting of a saturated ring and an unsaturated ring, wherein said ring may be substituted.

This application is a continuation of application Ser. No. 850,673, filed Aug. 15, 1969, now abandoned.

BACKGROUND OF THE INVENTION

1. Field of the Invention

This invention relates to a process for hardening gelatin.

2. Description of the Prior Art

Gelatin is used in the manufacture of various elements of photographic light-sensitive materials, such as silver halide emulsion layers, emulsion-protective layers, filter layers, anti-halation layers, backing layers, subbing layers of a film base or baryta layers of printing paper. Such gelatin-containing photographic light-sensitive materials are often treated with various aqueous solutions which may vary in pH and in temperature. If the gelatin-containing layer has not been treated with a hardener, it will be excessively swollen in an aqueous solution and will become fragile and, in a processing bath at a high temperature, will be completely dissolved therein.

There have hitherto been known numerous compounds which harden gelatin and thereby enhance the water-resistance of gelatin film. Chrome alum and like inorganic compounds, formaldehyde, glyoxal and like aldehydes, and mucochloric acid, 2,3-dihydroxy-1,4-dioxane and aldehyde-like analogues are examples of such compounds and they are well known as "hardeners" in the manufacture of photographic light-sensitive materials. However, the known hardeners have certain drawbacks. For instance, they exhibit undesirable effects on the properties of a photographic photosensitive material, namely, an increase in fog, a decrease in photographic sensitivity or so called "post hardening" owing to the slowness of the hardening

reaction, a loss of their hardening ability when added with certain photographic additives, or they are satisfactory with respect to enhancement of the water-resistivity of the photographic light-sensitive material but insufficient with respect to improvement of mechanical strength such as scratch-resistivity.

The principal object of the present invention is to provide a novel hardener for gelatin which will afford excellent water-resistivity and scratch-resistivity without any undesirable effects on the properties of the photographic light-sensitive material.

SUMMARY OF THE INVENTION

The present invention provides a process for hardening gelatin by reacting the gelatin with a novel compound represented by the formulae:

wherein R₁ represents a hydrogen atom, an alkyl group, a halogen-substituted alkyl group, an alkoxyalkyl group, an aryl group or an aryloxyalkyl group; R₂ represents an alkyl group, a halogen-substituted alkyl group, an alkoxyalkyl group, an aryl group or an aryloxyalkyl group; and Z represents the non-metallic atoms requisite for forming a saturated or unsaturated carbon ring, which may be substituted.

Detailed Description of the Invention

Accordingly, in accordance with the present invention, it is possible to enhance both the water-resistivity and the scratch-resistivity of gelatin-containing layers or gelatin-moldings.

The novel hardeners of the present invention will be exemplified by the following compounds.

Compound (1)

Compound (2)

Compound (3)

Compound (4)

Compound (5)

3

Compound (6)

Compound (7)

Compound (8)

Compound (9)

Compound (10)

Compound (11)

Compound (12)

Compound (13)

The novel hardener of the present invention exhibits a good hardening effect without any undesirable effects on the photographic properties, such as sensitivity, tone, storage stability and fog, of a photo-emulsion, even if added to a silver halide photo-emulsion. The novel hardener has the excellent characteristic that it quickly hardens gelatin after drying by virtue of its high activity. This quick hardening ability is especially important in the manufacture of photo-sensitive material of stabilized quality and free from "post hardening."

The hardener of the present invention would not lose its hardening ability at all, even in the presence of other photographic additives. In addition, a gelatin-containing coating layer or gelatin-moldings which have been hardened in accordance with the present invention have the desirable characteristics that they have been improved to a great extent not only in water-resistivity but also in mechanical strength, such as scratch-resistivity compared with that before hardening. This is a particularly important advantage in the manufacture of various light-sensitive materials which are to be rapidly treated in an automatic photographic processing machine under conditions of high pH and high temperature, and those which should have a high scratch-resistivity withstanding the rapid treatment without any surface injury, and in the manufacture of cinematographic positive light-sensitive materials which are required to have a film surface of high mechanical strength withstanding repeated projections.

4

The novel hardener of the present invention may be synthesized by reacting 1,2-dihydroxylalkane derivatives with glyoxal, (a) under reduced pressure on a phosphorous pentoxide or other drying agent, as disclosed in the Journal of the Chemical Society, p. 1,036 (1955), or (b) with heating.

The synthesis of the hardener compounds of the present invention will now be illustrated by the following synthesis examples.

10

SYNTHESIS EXAMPLE I

(Synthesis of Compound (1))

A mixture of 55.3 g. of 3-chloro-1,2-propanediol and 72 g. of a 40% aqueous glyoxal solution was held in 15 vacuo on phosphorus pentoxide until it was substantially solidified. The solidified material was added into a small volume of acetone and filtered to obtain 50 g. of white crystals. The crude crystal thus obtained was recrystallized from 50 ml. of isopropanol to obtain 72 g. of pure 20 Compound (1) (melting point 97-99° C.).

Elementary analysis as $C_5H_9ClO_4$: Calculated C: 35.61%, H: 5.34%. Found C: 35.76%, H: 5.47%.

SYNTHESIS EXAMPLE II

(Synthesis of Compound (2))

70 g. of pure Compound (2) (melting point 96-97° C.) was obtained by utilizing a procedure as in the synthesis of Compound (1) except that 73 g. of 1,2-octanediol (boiling point 102° C./1.5 mm. Hg), prepared by oxidizing 1-octane with performic acid was used in place of 30 3-chloro-1,2-propanediol, and ethanol was used as the solvent for recrystallization in place of isopropanol.

Elementary analysis as $C_{10}H_{20}O_4$: Calculated C: 58.82%, H: 9.80%. Found C: 58.70%, H: 10.01%.

35

SYNTHESIS EXAMPLE III

(Synthesis of Compound (3))

A mixture of 50 g. of 3-n-butoxy-1,2-propanediol (prepared from 3-chloro-1,2-propanediol and sodium n-butoxide and having a boiling point of 138-140° C./2.2 mm. Hg) and 50 g. of a 40% aqueous glyoxal solution was held in vacuo on phosphorous pentoxide for 4 days and then heated under reduced pressure (to 80° C./ 5×10^{-2} mm. Hg) to eliminate volatile matter and, thereby, to obtain 45 g. of Compound (3) in the form of a colorless, syrupy, viscous liquid.

Elementary analysis as $C_9H_{18}O_5$: Calculated C: 52.42%, H: 8.74. Found C: 52.15%, H: 8.91%.

50

SYNTHESIS EXAMPLE IV

(Synthesis of Compound (4))

A mixture of 6.9 g. of 2-phenyl-1,2-ethanediol and 10 ml. of water was heated on a water bath and the aqueous solution thus formed was cooled to room temperature. 55 The aqueous solution was added into 7.0 g. of a 40% aqueous glyoxal solution and heated at 50° C. for 2 hours. The solidified reaction product was washed with a small volume of acetone and there was obtained 7.2 g. of white crystal. The crude crystal was recrystallized from 50 ml. of ethanol to obtain 4.6 g. of pure Compound (4), having a melting point of 146.5° C.

Elementary analysis as $C_{10}H_{12}O_4$: Calculated C: 61.22%, H: 6.12%. Found C: 61.12%, H: 5.90%.

65

SYNTHESIS EXAMPLE V

(Synthesis of Compound (5))

A crude product (melting point 114-117° C.) of Compound (5) was obtained by repeating the procedure as in the synthesis of Compound (1), as mentioned above, except that 84 g. of 3-phenoxy-1,2-propanediol (prepared from 3-chloro-1,2-propanediol and sodium phenoxide and having a boiling point of 185-187° C./15 mm. Hg) was used in place of 3-chloro-1,2-propanediol. By recrystallizing from acetone, there was obtained 64 g. of white

pure Compound (5), having a melting point of 125-125.5° C.

Elementary analysis as $C_{11}H_{14}O_5$: Calculated C: 58.41%, H: 6.19%. Found C: 58.40%, H: 6.13%.

SYNTHESIS EXAMPLE VI

(Synthesis of Compound (6))

23.2 g. of trans-1,2-cyclohexanediol was dissolved into 15 ml. of water and the resulting aqueous solution was mixed with 29 g. of a 40% aqueous glyoxal solution and held in vacuo on phosphorous pentoxide. After 3 days, the mixture was solidified and there was obtained a white crude product of a melting point 88-95° C. By recrystallization from 20 ml. of water, there was obtained 23 g. of pure Compound (6), having a melting point of 97-100° C.

Elementary analysis as $C_8H_{14}O_4$: Calculated C: 55.17%, H: 8.05%. Found C: 54.66%, H: 8.09%.

SYNTHESIS EXAMPLE VII

(Synthesis of Compound (7))

16.5 g. of the pure Compound (7) of a melting point 136-136.5° C. was obtained in the same manner as in the synthesis of Compound (6), as mentioned above, except that 22 g. of catechol was used in place of trans-1,2-cyclohexanediol.

Elementary analysis as $C_8H_8O_4$: Calculated C: 57.14%, H: 4.76%. Found C: 57.03%, H: 4.68%.

SYNTHESIS EXAMPLE VIII

(Synthesis of Compounds (8)-(13))

Compounds (8)-(13) of this invention were also prepared by similar methods as previously described. The results are summarized in the following table.

HARDNERS (8)-(13), OBTAINED BY THE REACTION OF GLYOXAL AND THE FOLLOWING 1,2-GLYCOLS

Reactant	Purified products			Analysis, percent			
	Compound No.	M.P. (° C.)	Yield, percent	Calcd.	Found	C	H
1,2-glycols							
2,3-butanediol	(8)	(¹)	70	48.65	48.28	7.85	
2,3-pentanediol	(9)	(¹)	65	51.85	51.38	8.42	
3-n-dodecyl-1,2-propanediol	(10)	80-82	33	64.15	63.80	10.81	
1,2-dodecanediol	(11)	104-104.5	62	64.62	64.58	10.71	
1,2-octadecanediol	(12)	90-90.5	55	69.77	69.99	11.97	
4-tert-butylcatechol	(13)	114-116	51	64.29	7.14	64.27	7.88

¹ Syrupy liquid.

The hardener of the present invention may be used in any amount, though preferably, in an amount of from 0.1 to 10% by weight of gelatin. The hardener may consist of a single compound or of a mixture of two or more compounds and may be used either alone or in combination with known hardeners. The hardener may be used in the form of an aqueous solution or a solution in an organic solvent, such as an alcohol or a ketone. The photographic emulsion to which the hardener of the present invention is suitably added may be any silver halide, containing one or more halides, e.g., silver bromide, silver iodide, silver bromochloride, silver iodobromide, silver, chloro-iodo-bromide, and the like, and it may also contain chemical sensitizers, optical sensitizers, anti-foggants, coating aids, stabilizers, plasticizers, developing accelerators, toning agents, and like conventional additives.

The hardener of the present invention may be used not only in photographic light-sensitive materials but also for the hardening of gelatin-containing coating layers, such as those of a color filter and a baryta paper, and, further, for the hardening of gelatin-containing moldings, such as gelatin capsules and gelatin sheets.

The present invention will be further illustrated in more detail by the following examples.

EXAMPLE 1

To separate aqueous gelatin solutions, each containing 80 g. of gelatin per kg. of solution, were added, respectively, a known hardener compound (mucochloric acid) and Compounds (1) and (7) of the present invention, in the amount shown in the following Table. The solutions were separately applied to a subbed cellulose triacetate film in such an amount as to provide a dry coating film of a thickness of 10 microns, and then the composite was dried to form specimens of coated film.

The thus-formed specimens were aged at room temperature for 1 day, 5 days or 14 days, or under accelerating conditions for 2 days, and thereafter the melting point of the gelatin film was determined in a 2% aqueous solution of $Na_2CO_3 \cdot H_2O$ whose temperature was rising at a rate of 1° C./min. On the other hand, the specimens aged under accelerating conditions were subjected in a dry state or after being soaked in a 2% aqueous solution of $Na_2CO_3 \cdot H_2O$ for 10 minutes, to a determination of scratch-resistivity. In the determination of scratch-resistivity, there were used a needle having on its point end a diamond ball having a radius of 0.05 mm. for the dry specimen, and a needle having on its point end a stainless steel ball having a radius of 0.5 mm. for the soaked specimens. The needle was forced perpendicularly to the surface of the gelatin film and then moved in a direction parallel to the surface of the gelatin film at a speed of 5 mm./second. The load on the needle under which the gelatin film was injured was determined (hereinafter, the load under which the specimen of dry gelatin film was injured is referred to as the "dry scratch-resisting strength"; and the corresponding load to the specimen of gelatin film soaked in the aqueous alkaline solution is referred to as the "wet scratch resisting strength").

74

<90

<90

The results obtained are summarized in the following Table.

55	Compound	Amount (mole/kg.)	Room temperature for—			
			1 day	5 days	14 days	Accelerating conditions ¹
None (control)	0	35	35	35	35	36
Mucochloric acid	10^{-3}	37	45	51	58	
Do	2×10^{-3}	40	51	62		73
Compound:						
(1)	10^{-3}	44	57	57		59
(1)	2×10^{-3}	50	69	72		74
(7)	10^{-3}	70	82	85		<90
(7)	2×10^{-3}	80	85	<90		<90

65 SCRATCH-RESISTING STRENGTH (g)

Accelerated aging conditions (50° C., 80% RH, 2 days)

70	Dry:	Wet	
		25	50
25	-----	12	
25	-----		95
25	-----	100	
30	-----		110
30	-----		135
50	-----	125	
50	-----		150

The above table indicates that the compounds of the present invention have a quick hardening effect compared with the known hardener compound and give a hardened gelatin film having higher dry and wet scratch-resisting strengths.

EXAMPLE 2

To separate photo-emulsions each containing 75 g. of gelatin and 60 g. of silver bromide per kg. of emulsion, were added in the amounts listed in the following Table, a known hardener compound (2,3-dihydroxy-1,4-dioxane) and Compounds (2), (4) and (6) of the present invention, respectively, and the emulsions were separately applied to a subbed cellulose triacetate film in such an amount as to provide a dry coating film of a thickness of 10 microns, and then dried to form specimens of dry films. The melting points of the emulsion films in a 2% aqueous solution of $\text{Na}_2\text{CO}_3\text{H}_2\text{O}$ were measured on the specimens aged at room temperature of 3, 7 and 14 days; and the melting points of the emulsion films and dry scratch-resisting strengths were measured on the specimens aged under accelerated conditions for 2 days. On the specimens aged at room temperature for 30 days, the photographic properties were determined by developing at 20° C. for 10 minutes with a developer of the following formulation, and then fixing and washing with water.

	G.
N-methyl-p-aminophenol sulfate	1.0
Sodium sulfite (anhydrous)	75.0
Hydroquinone	9.0
Sodium carbonate monohydrate	30.0
Potassium bromide	5.0
Water to form a solution of 1 liter.	

The results obtained are summarized in the following Table.

Specimen number	Compound	Amount (mol/kg.)	Room temperature for—		
			3 days 7 days 14 days		
			Melting point (° C.)		
1	None (control)	0	35	35	35
2	2,3-dihydroxy-1,4-dioxane	10 ⁻³	39	45	50
3	do	3×10 ⁻³	41	49	59
4	Compound (2)	10 ⁻³	45	56	58
5	do	3×10 ⁻³	55	68	70
6	Compound (4)	10 ⁻³	47	60	61
7	do	3×10 ⁻³	58	75	75
8	Compound (6)	10 ⁻³	43	54	57
9	do	3×10 ⁻³	50	67	68

Specimen number	Accelerated aging conditions (50° C., 80% RH, 2 days)			Photographic properties		
	Melting point (° C.)	Dry scratch-resisting strength (g.)	Relative sensitivity			
				γ	Fog:	
1	36	25	100	2.23	0.10	
2	57	25	95	2.00	0.09	
3	70	25	91	1.96	0.08	
4	59	90	96	2.05	0.08	
5	71	90	94	1.98	0.08	
6	63	80	98	2.10	0.08	
7	76	80	96	2.05	0.07	
8	58	80	95	2.08	0.09	
9	70	80	93	2.05	0.08	

As indicated by the above Table, the specimens containing the compounds of the present invention (Specimens No. 4 to 9) exhibited a quick hardening and a high scratch-resisting strength, compared with the control specimen (Specimen No. 1) and those having a known hardener compound (Specimens Nos. 2 and 3). Further, the compounds of the present invention had little undesirable effects on the photographic properties.

EXAMPLE 3

To separate photographic emulsions, each containing 75 g. of gelatin and 62 g. of silver iodobromide, were added known hardener compounds (formaldehyde and mucochloric acid), and Compounds (3), (5), and (6) of the present invention, in the amounts listed in the following Table, respectively, and the emulsions were applied separately to a subbed cellulose triacetate film in such an amount as to provide a dry coating film of a thickness of 10 microns and then dried to form specimens.

The melting points of the emulsion films in a 2% aqueous solution of $\text{Na}_2\text{CO}_3\text{H}_2\text{O}$ were measured on the specimens aged at room temperature for 3, 7 and 14 days; and the melting points and scratch-resisting strengths were measured on the specimens aged under accelerating conditions.

The photographic properties were determined on the specimens aged at room temperature for 30 days by developing at 20° C. for 10 minutes using a developer as in Example 2, and then fixing and washing with water.

The results obtained are summarized in the following Table.

Specimen number	Compound	Amount (mol/kg.)	Room temperature for—		
			3 days 7 days 14 days		
			Melting point (° C.)		
1	None (control)	0	35	35	35
2	Formaldehyde	2×10 ⁻³	37	39	46
3	do	4×10 ⁻³	38	42	52
4	Mucochloric acid	2×10 ⁻³	37	38	40
5	do	4×10 ⁻³	39	42	45
6	Compound (3)	2×10 ⁻³	48	63	66
7	do	4×10 ⁻³	65	76	79
8	Compound (5)	2×10 ⁻³	42	65	68
9	do	4×10 ⁻³	57	73	74
10	Compound (6)	2×10 ⁻³	45	62	63
11	do	4×10 ⁻³	60	74	77

Specimen number	Compound	Amount (mol/kg.)	Accelerated aging conditions (50° C., 80% RH, 2 days)			Photographic properties		
			Melting point (° C.)	Scratch-resisting strength (g.)	Dry	Wet	Relative sensitivity	γ
45	35		25	13	100	1.90	0.12	
50			30	70	83	1.74	0.48	
63			30	85	70	1.63	0.67	
64			25	85	78	1.72	0.13	
70			30	92	63	1.64	0.20	
66			40	120	97	1.88	0.10	
79			50	130	94	1.86	0.10	
68			50	125	98	1.81	0.10	
50	75		60	145	95	1.88	0.09	
63			60	140	99	1.85	0.09	
77			65	155	96	1.90	0.08	

As indicated by the above Table, the specimens which contain the compounds of the present invention (Specimens Nos. 6-11) exhibited a quick hardening effect and a high scratch-resisting strength when compared with the control specimens (Specimen No. 1) and those containing the known hardener compounds (Specimen Nos. 2-5). Further, the compounds of the present invention had little undesirable effect on the photographic properties.

EXAMPLE 4

An aqueous gelatin solution containing 80 g. of gelatin per kg. of solution was uniformly applied to a subbed cellulose triacetate film base in such an amount as to provide a dry coating film of a thickness of 10 microns and then dried to form specimens. The specimen thus obtained was soaked for 1 minute in an aqueous solution containing 5 g. of Compound (1) of the present invention per 1 liter of solution, and then the melting point and dry and wet scratch resisting strengths of the gelatin film were determined. The melting point and wet scratch resisting strength were measured in a 2% aqueous solution of $\text{Na}_2\text{CO}_3\text{H}_2\text{O}$ after soaking the specimen in the aqueous solution as mentioned above, and without drying it. The

dry scratch-resisting strength was measured after soaking the specimen as mentioned above and drying it at room temperature. The results obtained are summarized in the following Table.

Compound	Scratch resisting strength (g.)		5
	Melting point (° C.)	Dry	
None (control).....	35	25	13
Compound (1).....	80	38	42

As indicated by the above Table, the specimen which has been treated with an aqueous solution containing the compound of the present invention exhibited a high melting point and a high scratch resisting strength compared with the specimen which had been treated with an aqueous solution not containing such a compound.

What is claimed is:

1. A process for hardening gelatin which comprises reacting the gelatin with a hardening amount of at least one compound represented by the formulae:

wherein R_1 represents a member selected from the group consisting of a hydrogen atom and an alkyl group having 1-16 carbon atoms; R_2 represents a member selected from the group consisting of an alkyl group having 1-16 carbon atoms and an alkoxyalkyl group wherein the alkoxy portion has 1-12 carbon atoms and Z represents non-metallic atoms requisite for forming an unsubstituted carbon ring selected from the group consisting of a saturated ring and an unsaturated ring.

2. The process as in claim 1, wherein said compound is a member selected from the group consisting of:

and

3. The process of claim 2, wherein said compound is

4. The process of claim 2, wherein said compound is

5. The process of claim 2, wherein said compound is

6. The process of claim 2, wherein said compound is

7. The process of claim 2, wherein said compound is

8. The process of claim 2, wherein said compound is

9. The process of claim 2, wherein said compound is

10. The process of claim 2, wherein said compound is

11. The process of claim 2, wherein said compound is

12. A process as in claim 1, wherein said compound is present in an amount of from about 0.1 to about 10% by weight of said gelatin.

13. A process as in claim 1, wherein said compound is in the form of an aqueous solution.

14. A process as in claim 1, wherein said compound is in the form of an organic solution.

15. The process as in claim 1 wherein said alkyl substituent contains at least 4 carbon atoms.
